CHARLES B. JACOBS, OF BLOOMFIELD, NEW JERSEY, ASSIGNOR, BY MESNE ASSIGNMENTS, TO AIR REDUCTION COMPANY, INCORPORATED, A CORPORATION OF NEW YORK.

PROCESS OF FORMING NITROGEN COMPOUNDS.

1,354,561.

Specification of Letters Patent.

Patented Oct. 5, 1920.

Application filed August 19, 1916. Serial No. 115,758.

To all whom it may concern:

Be it known that I, CHARLES B. JACOBS, a citizen of the United States, residing at Bloomfield, in the county of Essex and State 5 of New Jersey, have invented certain new and useful Improvements in Processes of Forming Nitrogen Compounds, of which the following is a full, clear, and exact description, such as will enable others skilled 10 in the art to which it appertains to make and use the same.

This invention relates to processes for the production of nitrogen compounds, and with respect to its more specific features to a 15 process for the production of alkali metal cyanids.

One of the objects of the invention is the provision of a practical process by means of which may be effected the direct combination 20 of free, or elementary, nitrogen with alkali metal compounds to form cyanids.

Another object of the invention is the provision of an efficient process for the production of a mixture of an alkali metal and 25 carbon in such intimate relation as when treated to facilitate the production of cyanids.

Another object of the invention is the provision of a practical process for the 30 direct combination of free nitrogen with alkali metal compounds to form cyanids, and which by a slight modification will result in the production of cyanamid.

Other objects will be in part obvious and 35 in part pointed out hereinafter.

The invention accordingly consists in the several steps and the relation and order of one or more of such steps with relation to each of the others thereof, which will be 40 exemplified in the hereinafter disclosed process, and the scope of the application of which will be indicated in the claims that follow.

In the accompanying drawing forming 45 part of this specification, there is shown an apparatus suitable for carrying out the process herein disclosed.

It is well known that the inert character 50 of free, or elementary, nitrogen has heretofore prevented its direct combination with other elements, except in meagre traces, without the influence of catalytic agents, or the electric spark, or silent discharge, or the

electric arc. Heretofore to effect combination of nitrogen with the alkali metals to 55 form cyanids or intermediate compounds from which alkali cyanids may be formed, it has been necessary to use some compound of nitrogen which will break up at the reacting temperature, and furnish nitrogen in 60 a nascent state.

By means of the present process alkali metal compounds may be effectively treated with nitrogen to produce different compounds of nitrogen, and further, metal compounds may be prepared or placed in such chemical or physical condition as will be 65 most suitable for treatment with nitrogen.

While any of the alkali metal compounds 70 may be treated in accordance with the present process so as to produce the related cyanids, as a practical illustration, the invention is herein disclosed in connection with the production of sodium cyanid from sodium carbonate, this latter furnishing a cheap and readily available compound for the purpose.

The sodium carbonate in a finely pulverized condition is intimately mixed with coking coal, also in a finely pulverized condition, sufficient coal being employed to furnish an excess of carbon over the theoretical amount required for carrying out the reactions hereinafter referred to. This mixture of sodium carbonate and coking coal is 75 placed in a suitable retort provided with an opening in the top for the escape of the volatile products of the coal and other gaseous products of the reactions, and with 80 a second opening in the bottom for the introduction of nitrogen. The retort is heated sufficiently to expel the volatile elements of the coal, a temperature of 700 degrees C. being found to be sufficient for the purpose. When all the volatile matter of the coal has 85 been expelled, there results a porous composition of coke, sodium carbonate, and some sodium oxid, the oxid resulting from the reduction of some of the carbonate during the coking operation. This porous mass, or mixture, of the alkali metal compound and carbon contains the sodium compounds 90 trapped within the cell walls of the coke, each particle of finely divided sodium compound being surrounded, as it were, by an 95 envelop of porous carbon. Thus the sodium

100

105

105

compound and the carbon are in the most favorable condition for intimate physical contact between the two, and when the nitrogen is turned into or associated with such a mixture, the nitrogen as well is brought into intimate contact with the carbon and the compound by reason of the porosity of the mass. Thus the sodium compounds may be said to be prepared in a physical condition facilitating their change of form and their passage into a nascent state in intimate physical and chemical contact with nitrogen and carbon.

Having obtained the intimate mixture of the alkali metal compound with carbon, as just explained, the temperature of the mixture in the retort is raised and nitrogen is then introduced into the bottom of the retort through the lower opening referred to, a degree of heat being employed sufficient to produce the alkali metal in a nascent state, a temperature of between approximately 940° C. and 950° C. being suitable for this purpose. Economy of operation is secured by first raising the temperature of the porous mass in the retort to approximately 800° C., and then introducing the nitrogen, the temperature being subsequently brought to approximately between 940° C. and 950° C. as rapidly as possible. As before stated, the nitrogen will come into intimate contact with the sodium compounds and carbon owing to the porosity of the mixture. The sodium compounds in contact with carbon at the temperature referred to are reduced from carbonate to oxide and pass momentarily into the metallic state, and being thus in a nascent condition in intimate contact with carbon and nitrogen they combine to form sodium cyanid.

The total reaction which takes place by the process above explained may be expressed by the following equation:

It is believed that the total reaction takes place in three phases, as follows:

It will be seen that phases (2) and (3) take place simultaneously whereas phase (1) may be carried out separately from phases (2) and (3) and in separate retorts in the absence of nitrogen by extending the coking operation in the first step of the process at a higher temperature. The resulting porous mass of sodium oxide and carbon may then be charged into a second retort for the performance of phases (2) and (3).

It is found that an excess of nitrogen and carbon over that required by the above equations facilitates the process if it is not

absolutely essential. An insufficient supply of nitrogen may result in the formation of metallic sodium in phases (2) and (3). While nitrogen may be introduced under normal conditions of pressure, its introduction under an increased pressure, a pressure, say, of from 10 to 15 lbs. per square inch will, however, be found to increase the velocity of the reaction, and consequently increase the yield of cyanid for a given time. The pressure seems to cause a more rapid penetration and contact of the nitrogen with porous composition of the sodium compounds and carbon, and also quickens the expulsion of the CO from the retort.

An insufficient supply of carbon may result in the production of sodium cyanamid in phases (2) and (3), and advantage of this fact may be taken, and sodium cyanamid produced from which ammonia is readily obtained, as will be seen from writing the reaction of phases (2) and (3) in one equation using one carbon less than is required to form sodium cyanid:

It is to be understood that nitrogen in a free, or elementary, state is employed in phases (2) and (3) of the process, although the association of some other gases with the nitrogen may be permitted provided they are not such as to interfere with the formation of the alkali cyanid. The nitrogen of the air may be employed, and may be separated from the other constituents of the air in any manner which will produce the nitrogen in a condition to be introduced into the retort. One way of obtaining such nitrogen is by the use of a two cylinder internal combustion engine of the four-cycle type in which gasolene or other fuel is employed. One of the cylinders of the engine is arranged to work as a compressor on the exhaust gases from the other cylinder. The mixture of fuel and air fed to the motor cylinder is so regulated that the exhaust gases will be composed of substantially a mixture of nitrogen and carbon dioxid. This mixture is passed directly to a cooler and a set of scrubbers containing glass wool and caustic soda or other compounds which will absorb CO₂ for removing carbon particles and carbon dioxid. The cleaned gas now substantially pure nitrogen is passed into the compressor cylinder of the engine and compressed to from 100 to 150 lbs. per square inch and passed to a gas storage tank for delivery to the retort as needed. It may be stated that the removal of carbon dioxid in the scrubbers may be dispensed with, and the mixture of nitrogen and carbon dioxid passed directly into the storage tank. Under such circumstances the mixed gas is delivered to the furnace as needed through a superheater filled with incandescent coke.

In the superheater the carbon dioxide is broken up into carbon monoxide which does not interfere with the formation of cyanids by the action of nitrogen on alkali compounds as hereinbefore described.

Referring now more specifically to the drawings, an apparatus is shown for efficiently carrying out the process hereinbefore described. It is preferable to perform the first step of the process, that is the coking of the charge so as to obtain the intimate mixture, of alkali metal compound and carbon in a furnace or retort separate from that in which phases (2) and (3) are performed, and to carry the first step of the process sufficiently far to not only drive off the volatile matter of the coal, but also to work into the first phase of the reactions, and to reduce as much of the sodium carbonate to oxid as possible. For this purpose ordinary coal gas retorts may be employed. The coking coal used should contain a high percentage of fixed carbon, say from 70 to 78 per cent, and should be as low in mineral matter and sulfur as possible. A charge is made up to contain approximately 60 to 64 per cent. by weight of sodium carbonate, and 40 to 36 per cent. by weight of coking coal. With a high volatile matter coal, a part of the coal may be replaced by some other form of fixed carbon as, for example, the charge may contain 60 per cent. sodium carbonate, 34 per cent. coking coal, and 6 per cent. charcoal. Emphasis is laid on the fact that the best results are obtained by having all the constituents of the charge in finely pulverized condition and intimately mixed. Such a charge is then placed in the coal gas retort and heated to about 700 degrees C. until all of the volatile matter of the coal is expelled and a considerable portion of the sodium carbonate reduced to oxid. This point is indicated by the diminution of the blue flame of CO produced by the first phase of the reaction, that is,

burning off at the outlet of the retort. This operation may require from 5 to 7 hours, depending on the character of the coking coal used, and the bulk of the charge, and after the operation the contents of the retort will show approximately the following composition:

55 24% sodium carbonate,
42% sodium oxid,
34% of carbon.

There is thus obtained an intimate mixture of alkali metal compound and carbon which may be stored in air-tight bins for future association with nitrogen as before explained, or may be transferred directly to the furnace illustrated in the drawing, in which the numeral 1 indicates the drum or

oven thereof. In the embodiment illustrated, the numeral 2 indicates the outer walls of the furnace composed of fire brick, or other material, having a high resistance to fusibility by heat, the drum 1 standing vertically therein spaced from the lateral walls thereof and surrounded by a protective shell of aluminum oxid (Al_2O_3). In the combustion chamber 3 of the furnace is placed an effective heat radiating substance, such as thermite slag, in position to be heated by a producer gas flame introduced through the burners 4, the latter communicating with a suitable supply of gas, as producer gas. Above and below the furnace the drum 1 is closed by covers 5 and 6 which may be hinged thereto and secured in position by clamps 7 and 8 which latter may be removed to permit the covers 5 and 6 to be moved to uncover the openings. The oven 1 may be charged through an opening closed by a removable plug 9 and the temperature of the mass in the furnace may be indicated by means of a thermo couple 10 connected with a pyrometer 11, the thermo-couple projecting through the cover 5. The numeral 11' indicates a pressure gage communicating with the interior of the oven, and 12 indicates a pipe communicating with the oven and carrying a safety valve 13. Communicating with the pipe 12 is a pipe 13' provided with a gate valve 14 which is adapted to control the exit of products of combustion from the furnace. The CO emerging from the pipe 13' may be ignited to serve as an indicator of conditions in the furnace. When it is desired to discharge the furnace, the clamp 8 may be removed whereupon the cover 6 will drop and the contents of the oven fall out.

105 The numeral 15 indicates a gas storage tank for the storage of nitrogen, or for a mixture of nitrogen and CO_2 obtained from the combined internal combustion engine and compressor indicated generally by the numeral 16. At 17 and 18 are the scrubbers, the latter being connected to the tank 15 by a check valve 19. The numeral 20 indicates a reducing valve and meter in the pipe line 21 leading from the storage tank 15 to the oven 1.

110 The intimate mixture of sodium compound and carbon previously referred to is charged into the oven 1 through the opening covered by the plug 9, and the furnace brought to a temperature of approximately 800 degrees C., as indicated by the pyrometer 11. Nitrogen from the tank 15 is then admitted to the charge after passing the reducing valve, and the meter 20, the meter 125 serving to measure the quantity of nitrogen used and the reducing valve serving to obtain the pressure desired. As soon as the nitrogen is turned into the oven through the pipe 21 the temperature of the charge is 130

raised to approximately between 940° and 950° C. The reactions of phases (2) and (3) then begin to take place. The CO produced in the reaction is led off at the end of 5 the pipe 13' and serves as an indication of the progress of the reaction. When CO is no longer evolved the reaction is complete. The pressure gage 11' serves to indicate the pressure of nitrogen plus the pressure of 10 the CO evolved by the reaction going on. Ordinarily the relative amount of CO and nitrogen pressure is taken from time to time by closing the nitrogen inlet valve 19' and reading the internal pressure due to the 15 evolution of CO by the reaction; when this is *nil*, it shows the end of the reaction. The safety valve for the pipe 12 may be set to release at about 12 lbs. per square inch.

The length of time required to carry out 20 the (2) and (3) phases of the reaction varied somewhat by the character of the coke produced by the different coal, and the reaction may be carried nearly to completion or stopped at some intermediate point 25 when sufficient sodium cyanid for working has been formed. In any case the furnace product will be composed of a mixture of sodium cyanid, sodium oxid, sodium carbonate, and carbon. At the end of the given 30 period the contents of the furnace are discharged. When the formation of sodium cyanid has been carried to the proper point, the nitrogen is shut off and the inlet pipe 21 disconnected. The clamp 8 is then loosened 35 and the charge allowed to drop into an air tight container for cooling. A new charge is then placed in the furnace, and the operation of forming sodium cyanid repeated.

After the charge expelled from the 40 furnace has become cold, it is lixiviated with water, the temperature being kept below 30° C. The insoluble carbon residue is filtered off and the solution which contains sodium cyanid, sodium carbonate, and sodium hy- 45 drate is evaporated *in vacuo* and the sodium cyanid separated from the carbonate and hydrate by fractional crystallization. The sodium hydrate left in the solution is car- 50 bonated and added to the separated car- bonate, dried and used for making up subse- quent furnace charges.

Thus by the above described processes are accomplished, among others, the objects hereinbefore referred to.

55 As many changes could be made in carrying out the above process without departing from the scope of the invention, it is intended that all matter contained in the above description shall be interpreted as 60 illustrative and not in a limiting sense.

It is also to be understood that the language used in the following claims is intended to cover all of the generic and specific features of the invention herein de- 65 scribed and all statements of the scope of

the invention, which, as a matter of language, might be said to fall therebetween.

Having described my invention, what I claim as new and desire to secure by Letters Patent is:

70 1. In a process of forming alkali metal cyanid the method of preparing the furnace mixture which comprises, intimately commingling carbonaceous material and an alkali metal compound in a dry condition, and 75 heating the mixture while in a loose, pulverulent condition to expel the volatile constituents thereof.

2. In a process of forming alkali metal cyanid, the method of preparing the furnace 80 mixture which comprises, intimately commingling coking coal and an alkali metal compound, and heating the mixture while in a loose, pulverulent condition to expel the volatile constituents and produce a 85 porous coke having the alkali metal compound trapped within the cell walls thereof.

3. In a process of forming sodium cyanid, the method of preparing the furnace mixture which comprises, intimately com- 90 mingling coking coal and sodium carbonate, and heating the mixture while in a loose pulverulent condition to expel the volatile constituents and produce a porous coke having sodium carbonate and oxid trapped 95 within the cell walls thereof.

4. A process of forming alkali metal cyanid which comprises, intimately commingling carbonaceous material and an alkali metal compound, heating the mixture 100 while in a loose, pulverulent condition to expel volatile constituents, regulating the temperature to agglomerate the mixture without fusing and subsequently introducing nitrogen to the mixture while the latter 105 is maintained at an elevated temperature.

5. A process of forming alkali metal cyanid which comprises, intimately commingling coking coal and an alkali metal compound, heating the mixture while in a 110 loose, pulverulent condition to expel volatile constituents and produce a coke having the alkali metal compound trapped within the cell walls thereof and subsequently introducing nitrogen to the mixture while the latter is maintained at an elevated temperature.

6. A process of forming sodium cyanid which comprises, intimately commingling carbonaceous material and sodium carbo- 120 nate, heating the mixture while in a loose, pulverulent condition to expel volatile constituents, regulating the temperature to ag- glomerate the mixture without fusing, and subsequently introducing nitrogen to the 125 mixture while the latter is maintained at an elevated temperature.

7. A process of forming sodium cyanid which comprises, intimately commingling coking coal and sodium carbonate, heating 130

the mixture while in a loose, pulverulent condition to expel volatile constituents and to produce a coke having sodium carbonate and oxid trapped within the cell walls thereof and subsequently introducing nitrogen to the mixture while the latter is maintained at an elevated temperature.

In testimony whereof I affix my signature, in the presence of two witnesses.

CHARLES B. JACOBS.
